UNITED STATES PATENT OFFICE.

WILLIAM R. FOWLER, OF PHILADELPHIA, PENNSYLVANIA, ASSIGNOR TO
MARTIN J. MYERS, OF SAME PLACE.

CLOTH-CUTTING MACHINE.

SPECIFICATION forming part of Letters Patent No. 245,152, dated August 2, 1881.

Application filed January 4, 1881. (No model.)

To all whom it may concern:

Be it known that I, WILLIAM R. FOWLER, a citizen of the United States, residing in Philadelphia, Pennsylvania, have invented certain 5 Improvements in Cloth-Cutting Machines, of which the following is a specification.

My invention relates to certain improvements in cloth-cutting machines, similar to that described in my former applications for patent filed respectively on the 24th day of May, 1880, and the 15th day of November, 1880, the objects of my present improvements being too fully described hereinafter to need detailed preliminary explanation.

15 In the accompanying drawings, Figure 1, Sheet 1, is a perspective view of my improved cloth-cutting machine; Fig. 2, Sheet 2, a side view, partly in section, and drawn to a larger scale than Fig. 1; and Figs. 3 to 6, detached 20 views of different parts of the device.

A represents the table, the legs of which are furnished with wheels, those of one set of legs running on the floor and those of the other set being adapted to a grooved rail secured to the 25 floor, this rail having at intervals recesses for the reception of the end of a locking-bolt, a, on one of the legs, so that the table A can be adjusted longitudinally to any desired position in respect to the frame B and secured in such 30 position.

The table A is provided with a cloth-supporting bed, D, consisting of elastic wires projecting perpendicularly from a suitable backing, and of uniform length, so as to present a 35 level surface for supporting the cloth. This supporting-bed is similar in principle to that described and claimed in my application for patent filed November 15, 1880; but the present bed differs from the former one in using 40 comparatively stiff supporting-wires, separated or isolated from each other, so that the knife is at liberty to pass freely in any direction through the bed, and the wires can yield in any direction. I have found wire of from fourteen to sixteen gage to answer well in practice for the formation of the cloth-supporting bed.

The spaces between the wires should be slightly in excess of the width of the knife-blade, so as not to interfere with the free turn-

ing of said knife when it occupies a position between the wires. In the event of the front edge of the knife-blade during its forward movement coming into contact with one of the wires, the latter, owing to its elasticity, will 55 be thrust aside in one direction or the other, Fig. 5, and the movement of the knife will not be impeded.

I use a cutting-knife, b, having a series of step-like projections, x, the upper edges of which are sharpened so as to cut on the upward movement of the knife, a plate, d, which rests on the top of the material, serving as an abutment, against which said material is pressed by the action of the knife in cutting. 65 The plate d is secured to or forms part of a standard, e, hung to a frame, E, and free to turn in respect thereto, the shaft b', to which the cutter b is attached, being adapted to bearings in said frame E, and being free both to 70 move vertically and to turn in said bearings as the plate d is turned, the knife b working in a slot in said plate.

The frame E is secured to the outer end of an arm, F, a yoke on the opposite end of which 75 embraces a flange on an arm, G, another flange on the latter being embraced by a yoke on a plate, H, pivoted to a swinging frame, J, hung to the fixed frame B. The arm F is thus free to slide on the arm G, and the latter on the 80 pivoted plate H, as the knife follows the lines of a pattern marked on the cloth, the yokes being preferably furnished with anti-friction rollers to facilitate this sliding movement of the arms.

85 The reciprocating motion is imparted to the cutter-shaft b' by means of a crank on a shaft, f, adapted to bearings in the frame E and in a frame, I, on the arm F, said shaft f being driven by means of bevel-gearing from a vertical shaft, g, also adapted to a bearing in the frame I, power being applied to the latter shaft from the main driving-shaft M on the frame J through the medium of a flexible transmitter N, similar in general principle to that described 90 and claimed in my application for patent filed May 24, 1880. Certain details in the construction of this transmitter, however, I have modified in the present case. Thus, the transmitting-spindle h is made in two parts, one of which 95 100

is tubular and adapted for the reception of the other part, so that the spindle can be lengthened or shortened to suit different heights of tables A and frames B, the two parts being secured in position after adjustment by means of a pin or other fastening, for it must be understood that this adjustment is entirely independent of the movement of the spindle in respect to the driving-pulley due to the movement of the cutter, such movement being effected, as before, by the sliding of a plate at the upper end of the spindle on pins *i* carried by the pulley. These pins are, however, in the present transmitter connected together at 15 the bottom by a plate, *i'*, so as to increase their stability.

It will be observed that the pivots of the swinging frame J are in line with the driving-shaft M, so that the said frame can be turned 20 from the position shown by full lines to that shown by dotted lines in Fig. 1 without deranging the driving-belts. A segmental guide-rod, J', serves to steady the frame J during its movement, and a suitable locking device, *j*, is 25 used to secure the frame in either of its two positions; and it may also be adapted to notches on the rod J', if desired, so as to secure the frame J in positions between the two extremes of movement shown.

30 The object of using the swinging frame J in conjunction with the sliding arms F G is to permit cutting over a large area without moving the table A or the cloth thereon, for it will be observed that when the cutter has operated 35 on the cloth over the area permitted by the arms F G when the frame J is in one of its extreme positions said frame may be swung into a new position, and the area reached by the cutter thus extended until the frame occupies 40 the opposite extreme. The frame may then be restored to its first position and the table moved so as to bring a new portion of the cloth under the action of the knife.

Any desired thickness of cloth may be cut 45 with my improved machine, the arm F being adjustable vertically in respect to the arm G, owing to the use of the slotted standard *m* and bolt *m'*, for securing the said arm F to the yoke on the arm G, so that the pressure of the 50 plate *d* on the cloth may be accurately governed.

I prefer to make the operating-crank of the knife adjustable, so as to vary the length of stroke as desired, and to so construct 55 the knife *b* in respect to the length of stroke that the lowest cutting-surface of the knife will pass above the top layer of cloth on the upward stroke and the highest cutting-surface beneath the lower layer of cloth on the 60 downward stroke; and the knife-blade should project so far beneath the lowest cutting-surface that when the knife is at the top of its stroke the lower end of the blade will not be raised above the top of the supporting-bed. By this means I prevent the contact of the 65 knife with the tops of the wires forming the supporting-beds.

By providing the cutting-blade with a series of step-like cutting-edges the hold taken on the material in starting the cut is but slight, 70 and gradually increases as the blade is raised, and the operating crank comes into position for more effective action.

The front edge of the knife is made with a projection, *x'*, so as to prevent the wires from 75 coming into contact with and dulling the sharpened portion of said front edge adjacent to the lowest cutting-surface, *x*. (See Figs. 3 and 6.)

Any of the forms of hooked knives shown 80 in my former application for patent, filed November 15, 1880, may be used in the present machine.

Immediately in the rear of the plate *d* is a plate, *p*, which is guided on the standard *e*, 85 and can be raised and lowered by means of a lever, *s*, hung to the operating-handle *S* on said standard. This plate is depressed by a spring, and is clothed on the under side with rubber, leather, or like substance, which will 90 exert the proper amount of friction on the surface of the cloth or other material being cut and prevent accidental movement of the knife and knife-carrier when the handle *S* is released. During the cutting operation the plate *p* is 95 held in its elevated position by the pressure of the thumb on the lever *s*, and the free movement of the plate *d* over the cloth is not interfered with. The lever may, if desired, be retained in this position by the engagement 100 of a pivoted catch thereon with the handle *S*. The plate *p*, when depressed, also serves as a guard to prevent the contact of the plate *d* with the supporting-bed in the event of the knife-carrier being moved off of the cloth. 105

In Fig. 4 of the drawings I have shown a modified form of cutting-knife, in which the blade *y* is made separate from the shank *y'*, the latter being bent 110 as to embrace the blade. In the rear of the shank are formed 115 slots *w*, adapted for the reception of a lug, *w'*, on the rear of the blade, so that when the cutting-edge of said blade becomes reduced by grinding said blade can be removed from the shank and the lug adapted to a slot above that formerly occupied, so as to properly elevate the cutting-edge. It will be understood 120 that the sides of the shank fit closely to the blade, so as not to interfere with the free passage of the same through the material in cutting. 125

Stiff fibers other than wire may be used for the supporting-bed *D*; but wires have been found to answer best in practice, and are preferred.

I claim as my invention—

1. A cloth-supporting bed consisting of a backing having wires secured thereto, but isolated from each other, as set forth, so as to permit the passage or turning of a knife-blade 130 without contact with the wires, as set forth.

2. The within-described cutting-knife, having a blunt lower end and a projecting face or faces sharpened on the upper edge, and adapted

- to cut on the upward movement of the knife, as specified.
3. A cutting-knife having a series of projections sharpened on the upper edges and adapted to cut on the upward movement of the knife, said projections receding from the lower to the upper portion of the knife in step-like form, as set forth.
4. A cutting-knife having a projecting cutting face or faces, x , adapted to cut on the upward movement of the knife, and a blunt edge, x' , projecting beyond the cutting-face of the knife, as set forth.
5. A cutting-knife consisting of a cutting-blade, y , and a shank, y' , embracing the same, said blade y being adjustable vertically in respect to the shank, as specified.
6. The combination of the blade y , having a lug, w , with the shank y' , having notches w , as set forth.
7. The combination of a permeable bed, substantially as described, a traversing knife having a projecting cutting portion or portions sharpened on top and adapted to cut on the upward movement of the knife, and an abutment, d , resting on the material, but free to move over the same, as specified.
8. The combination of the permeable bed, the abutment above the material, the knife cutting on the upward movement, and reciprocating devices, whereby said knife is operated without carrying the lower end of same above the bed, as specified.
9. The combination of a knife-carrier with a supporting structure comprising a series of arms adapted to slide on each other, the outer arm being secured to the knife-carrier, and the inner arm being pivoted, as set forth.
10. The combination of a knife-carrier with a supporting structure comprising a series of arms adapted to slide on each other, and a pivoted block or plate carrying said arms, and across which they are free to slide, as specified.
11. The combination of a knife-carrier, a supporting structure comprising a series of arms adapted to slide on each other and to swing on a pivot, knife-operating gearing carried by the outer arm, and a flexible power-transmitter, whereby said gearing is operated from a fixed point located above the pivot of the supporting structure, as specified.
12. The combination of the knife-carrier and its support with the flexible power-transmitting device, the spindle h of which is made in sections adjustable in respect to each other, as set forth.
13. The combination of a knife-carrier and a supporting structure comprising a series of arms adapted to slide on each other and to swing on a pivot, one or more of said arms being vertically adjustable to vary the height of the knife-carrier to suit different thickness of material, as set forth.
14. The combination of the table A, the frame B, the knife-carrier, the supporting-frame comprising a series of arms adapted to slide on each other, and a swinging frame, J, carrying said structure and the power-transmitting device, as set forth.
15. The combination of the table A, the fixed frame B, the knife-carrier, the supporting structure comprising a series of arms adapted to slide on each other and to swing on a pivot, and the swinging frame J, carrying the pivot of said supporting structure and the power-transmitting devices, as specified.
16. The combination of the table A, fixed frame B, the knife-carrier, the sliding arms, the swinging frame, and means for locking said frame in different positions, as specified.
17. The combination of the fixed frame B, the knife-carrier, the sliding arms, the swinging frame J, and the longitudinally-adjustable table A, as specified.
18. The combination of the plate l of the knife-carrier with the vertically-adjustable guard-plate protected on the under side, as set forth.
19. The combination of the plate d of the knife-carrier, the vertically-adjustable guard-plate p , the handle S, and the lever s , as specified.
- In testimony whereof I have signed my name to this specification in the presence of two subscribing witnesses.

WM. R. FOWLER.
